CLAIM

I claim the ornamental design for an imager for a vehicle, as shown and described.

DESCRIPTION

FIG. 1 is a front perspective view of an imager for a vehicle showing my new design;

FIG. 2 is a top and rear perspective view thereof;

FIG. 3 is a front elevation view thereof;

FIG. 4 is a rear elevation view thereof;

FIG. 5 is a first side elevation view thereof;

FIG. 6 is a second side elevation view thereof;

FIG. 7 is a top plan view thereof; and,

FIG. 8 is a bottom plan view thereof.

The broken lines depict portions of the imager for a vehicle in which the design is embodied that form no part of the claimed design.
